Primary Examiner — Marianne N Pandozzi*(74) Attorney, Agent, or Firm* — Bereskin & Parr
LLP/S.E.N.C.R.L., s.r.l.; Isis E. Caulder; Nicholas Aitken(57) **CLAIM**

The ornamental design for an aerator, as shown and described.

DESCRIPTION

FIG. 1 is a perspective view of an aerator showing my new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines in the drawings depict portions of the aerator that form no part of the claimed design.
